C. A. DEARBORN

BLINDSTITCH SEWING MACHINE

Filed May 17, 1921

Patented Sept. 11, 1923.

1,467,570

UNITED STATES PATENT OFFICE.

CHARLES A. DEARBORN, OF NEW YORK, N. Y.

BLINDSTITCH SEWING MACHINE.

Application filed May 17, 1921. Serial No. 470,285.

To all whom it may concern:

Be it known that I, CHARLES A. DEARBORN, a citizen of the United States, residing in the borough of Manhattan, city, county, 5 and State of New York, have invented certain new and useful Improvements in Blindstitch Sewing Machines, of which the following is a specification.

The present invention relates to improvements 10 in stitch forming mechanism for blind stitch sewing machines of the type covered by Patents No. 705,325 granted to me July 22, 1902, and No. 814,026 granted to me March 6, 1906.

Blind stitch sewing machines of the type 15 referred to have been in commercial use for a number of years, particularly for manufacturing clothing. These machines are operated at very high rates of speed and 20 are required to be extremely accurate in all details. To further insure the accuracy of this type of machine, the present invention improves the structure of the looper and its mounting to cause it to cooperate 25 more efficiently with the reciprocating upper feed mechanism of the machine.

In accomplishing the desired object, the 30 looper rod is formed at its forward end with an angular head offset slightly from the looper rod and shaped to accurately receive the channelled heel of the looper proper which is formed of a sheet steel stamping, longitudinally channelled for strength and stiffness and having a slot for passage of a 35 set screw which is threaded into the offset head of the looper rod.

The looper rod is provided, back of the offset head referred to, with a spherical bearing that is engaged by a spherical bearing 40 yoke formed upon the depending rock arm extending from an elongated bearing sleeve that is journalled upon an adjustable block carried in the sewing machine arm. This suspended bearing yoke is formed of 45 two plates separated in a plane transverse to the axis of the looper rod and formed with complementary spherical recesses on their inner faces to engage the ball of the rod and with openings in their faces for 50 the looper rod to project through. To permit the bearing yoke to operate in a vertical, longitudinal plane as close as possible to the plane of operation of the reciprocating upper feed bar, the inner edges of the 55 plates forming the yoke are cut away in a vertical plane so that the rocking bearing

yoke will operate in close proximity to the retaining disk fastened alongside of the bearing of the reciprocating feed bar. By this arrangement, the effective long bearing 60 for the rocking yoke is provided, while at the same time the parts are brought into close proximity so as to enable them to effectively cooperate with the least complications of movements. 65

In order that the invention may be fully understood, it will now be described with reference to the accompanying drawing. In said drawing—

Figure 1 is a detail sectional plan view of 70 a machine showing the improved looper.

Figure 2 is a side elevation of the same.

Figure 3 is a vertical, transverse, sectional view taken on the line 3—3 of Figure 2.

Figure 4 is an enlarged, detail view of a 75 part of the looper rod and removable looper.

The type of machine to which the present improvements apply is well known in the art and is illustrated in the patents above referred to. The drawing shows only sufficient of the machine to connect up the stitch forming mechanism to which the present improvements relate. 80

5 represents the forwardly projecting arm of the sewing machine frame and 15 the main driving shaft from which the operative parts receive motion. The shaft 15 carries the feed actuating eccentric 137, the needle actuating eccentric 53 and the looper actuating crank disk 18. A cylindrical block 32 90 is adjustably mounted in the sewing machine arm 5 and held in the desired adjusted position by means of the set screw 35. This block 32 carries an eccentric bearing pin 95 31 which projects laterally and horizontally from the arm 5 and has journalled upon it a sleeve 30 formed integral with the main portion of the downwardly projecting sectional bearing yoke presently to be described.

The bearing yoke referred to comprises a plate 50 formed integral with the sleeve 30 and a complementary removable plate 51 secured to the face of the plate 50 by means of set screws 55. Plates 50, 51 are formed with axial openings that are enlarged inwardly to form spheroidal recesses indicated at 60, 61 to receive and confine the bearing ball of the looper rod herein-after referred to. The inner edge of the sectional yoke 50, 51 is cut away in a vertical plane as indicated at 62 in Figure 3 of the drawing for the purpose of affording 100 105 110

room between the rocking yoke of the looper and the bearing of the upper feed member hereinafter described.

The crank disk 18 carries a crank arm 19 projecting from it at an angle of approximately 45 degrees and rigidly mounted upon the crank arm 19 is a crank pin 20 which is presented at an angle of about 45 degrees to the shaft 15. Freely swivelled upon the crank pin 20 is a sleeve 21 having pivoted to it at 21^a a yoke 22, to which is adjustably secured the rear end of the looper rod 25. The looper rod is formed adjacent to its forward end with a spherical bearing 38 which is freely journalled in the rocking yoke 50, 51 above referred to. The bearing between the ball 38 and the rocking yoke provides a form of universal joint, permitting the looper rod to move forwardly and backwardly with the rocking yoke while the looper rod rocks in the bearing yoke laterally and up and down in carrying out its stitch forming functions.

The extreme forward end of the looper rod is provided with an angular offset shoulder 70 which is shaped to receive the channelled heel of the looper proper 75. The looper proper is preferably formed of a sheet steel stamping, it being given the channelled formation for strength and rigidity and the looper fingers being properly shaped at the forward end of the curved looper arm. In the heel portion of the looper 75 is formed a slot 76, through which passes the set screw 77 threaded into a suitable opening in the angular head of the looper rod.

To properly illustrate the advantages of the improved looper mechanism, I have illustrated in the drawing the upper reciprocating feed device with which the improved looper cooperates. This feed device is substantially the same in general principle as the feed mechanism covered by my above named Patent No. 814,026 and comprises essentially a feed dog 130 projecting laterally from the forward end of a longitudinally movable rocking arm or bar 133. This arm or bar 133 is formed between its ends with an elongated slot 134 in which engages an anti-friction roller 135 mounted upon a pin or screw 138. Disks or washers 139 and 140 are also confined upon the screw 138 upon opposite sides of the feed bar 133 for confining and guiding it in its rocking reciprocations. The rear end of the feed bar 133 is formed with a yoke 136 which embraces the eccentric 137 upon the main driving shaft 15 above referred to.

60 Referring now particularly to Figure 3 of

the drawing, it will be observed that the cut-away portion 62 of the rocking bearing yoke of the looper permits the mounting of the looper in a plane close to and approximately parallel with the plane of operation of the feed bar 133. This close parallel relationship is very important from the standpoint of efficiency in a rapidly operating sewing machine. This mounting of the looper affords a desirable long bearing for the rocker 70 without interfering with the effectiveness of the universal joint upon which the looper is mounted.

I claim:—

1. In a sewing machine, the combination of a machine frame, a bearing pin projecting laterally from said frame, a rocker arm having an elongated bearing journalled upon said pin and a yoke depending from said bearing, a looper having a universal joint bearing in said depending yoke, and a feed bar mounted upon the machine frame between the frame and said depending yoke, said yoke being cut away on its inner edge to permit the close association of the looper and feed bar substantially set forth. 75

2. In a sewing machine, the combination of a machine frame, a reciprocating feed bar mounted approximately in a horizontal plane upon said frame, a rocker arm journalled upon said frame directly above said feed bar to rock forward and backward in a vertical plane approximately parallel with and alongside of said feed bar, said rocker arm comprising a depending yoke formed 95 with a spheroidal bearing socket and an inner cutaway face to permit the close association of said rocker arm and feed bar in said parallel planes, a looper rod having universal joint driving mechanism connected 100 with its rear end, a looper upon the forward end of said looper rod, and a spherical bearing between the ends of said looper rod which engages said bearing yoke of the rocker arm. 105

3. In a sewing machine, the combination of a machine frame, suitable feed mechanism, a looper comprising a looper rod mounted for loop forming motions and having at its forward end an offset, angular shoulder and a looper proper of substantially U-shape cross section formed of a sheet metal stamping and having a slotted, channelled heel fitting the offset shoulder of the looper bar and a set screw passing through the slot of the looper heel and threaded into the offset shoulder of the looper rod as set forth. 115

CHARLES A. DEARBORN.
